CLAIM

The ornamental design for a light system as shown and described.

DESCRIPTION

FIG. 1 is a bottom front perspective view of a light system showing the claimed design; and, FIG. 2 is a bottom plan view thereof.

The broken lines in the figures show portions of the light system and environment that form no part of the claimed design.

The dot-dash lines in the figures show boundaries that form no part of the claimed design.

FIGS. 1 and 2 are illustrated to show contrasting appearance. The gray-shaded portions and the stipple-shaded portions have different appearances. The stipple-shaded portions show areas emitting light.
